(57) **CLAIM**

The ornamental design for a display screen with icon, as shown and described.

DESCRIPTION

FIG. 1 is a front elevational view of a display screen with an icon showing my new design; and,
FIG. 2 is an enlarged, front elevational view of the icon of FIG. 1.

The broken lines shown in FIG. 1 represent the display screen and form no part of the claimed design.

1 Claim, 2 Drawing Sheets

FIG.1

FIG.2
